CAM DEVICE FOR CONTROLLING ELECTRIC CIRCUITS

Harold Dodimead Gaite, Taplow, England, assignor to British Telecommunications Research Limited, Taplow, England, a British company

Application August 29, 1951, Serial No. 244,193
In Great Britain September 6, 1950

5 Claims. (Cl. 200—46)

1

The present invention relates to cam devices and is more particularly concerned with cam devices arranged to control an electrical circuit or circuits.

The object of the invention is to provide a cam device in which the mass of the moving parts is reduced to a minimum and in which the acceleration of the cam follower on operation is reduced to a reasonable figure by simple means.

According to the invention, in a cam-operated switching device, a thin sheet supported by a base member having an electrical contact inset or insets is provided with one or more slots or cut-out portions aligned with said inset or insets and is arranged to co-operate with a cam follower for each slot and forming the other electrical contact, relative movement between the sheet and the cam follower or followers causing the latter to ride into and out of the slot or slots to complete the electrical circuit or circuits between the cam follower or followers and the contact inset or insets.

In one embodiment of the invention the sheet is in the form of a disc mounted on a rotatable spindle, a slot or slots being provided at the desired radius or radii from the centre of the disc, while the cam followers are stationary. The base member by which the disc is supported is fixed relative to the disc and carries contact pins of electric conducting material with which the followers contact as they drop into the corresponding slot.

Alternatively the base member is mounted for rotation with the disc and carries a contact inset or insets having substantially the dimensions of the slot or slots in the disc.

Preferably the cam followers are made of spring wire of circular cross-section, the free ends of the followers being bent to form an acute or an obtuse angle with the shank or are of narrow U-shape or of V-shape. Alternatively the followers may consist of spring-pressed balls. It is also preferred to contour at least the leading edges of the slot or slots or to make the leading edge flexible.

The invention will be better understood from the following description of several embodiments given by way of example only and taken in conjunction with the accompanying drawings comprising Figs. 1 to 9.

In the drawings,

Fig. 1 shows a plan view of one embodiment,

Fig. 2 shows a part-sectional side elevation of the embodiment of Fig. 1,

2

Fig. 3 shows a plan view of a second embodiment.

Fig. 4 shows a part-sectional side elevation of the embodiment of Fig. 3, and

5 Figs. 5 to 9 show various constructions of the cam-followers and the edges of the disc.

Referring first to Figs. 1 and 2, the device is shown as mounted on both sides of a plate 1 and comprises a circular disc 2 provided with slots or cut-out portions 3. The disc is made of conducting material, for instance, shim steel and is mounted for rotation on the spindle 4. The spindle 4 passes through the base or supporting member 5 which together with distance piece 6 is suitably secured by means not shown to a base 7 fitting within the circular housing 8 and suitably secured by screws (not shown) to the plate 1. The provision of the distance piece 6 enables terminals 9 to be secured to the underside of the base or supporting member, the terminals 9 being connected to the contact insets or pins 10 and to the controlled circuits. A suitable cover (not shown) would normally be provided for the housing 8. The cam followers 11 are made of spring wire and as shown in Fig. 2 the free ends are of narrow U-shape. The followers are threaded through holes in a mounting block 12 secured to the supporting member 5, the screws 13 enabling the position of the followers in the block to be adjusted. A terminal 14 is also secured to the block to enable connection to be made with one pole of the current source, the other pole being connected to remote ends of the controlled circuits the near ends of which are connected to the terminals 9. It will thus be seen that as the disc rotates contact will be made between the cam-followers and the conducting insets only where a slot in the disc passes beneath the cam follower. Where the disc is of conducting material, the pins in the supporting member will be adjusted so that their top surface is slightly below the level of the supporting member so that contact between the pins and the disc is avoided. Alternatively, of course, the disc may be made of insulating material but the advantage of using shim steel, namely that the disc may be made very thin and flexible, is thereby lost.

In the embodiment shown, the spindle 4 is continuously driven by means of an electric motor indicated at 15, the motor being secured by pillars 16 on the underside of the plate 1. The drive between the motor and the spindle includes a reduction gear and a friction clutch but as these form no part of the invention they are

not shown in detail but are indicated diagrammatically by 17.

In the embodiment, shown in Figs. 3 and 4, those parts which are shown in Figs. 1 and 2 are given the same reference numbers. In this embodiment the supporting member 20 and the disc 2 are mounted for rotation on the spindle 4. The contact insets in this case will have substantially the same dimensions as those of the slots in the disc and electrical connection therewith will be effected, for instance, by means of suitable brushes 21 mounted in an insulating block 22. The mounting block 12 is now secured to an individual support 23 mounted on the base 7. This arrangement has the advantage that there is no friction between the disc and the supporting member although, as will be seen from Fig. 1, friction is reduced to a minimum by recessing the supporting member at 18. It is also pointed out that with the embodiment of Figs. 1 and 2 there is no axial load on the spindle and the flexibility of the disc allows of axial float at all times.

Referring now to Figs. 5 to 9, these show enlarged views of various shapes of cam-followers and the shaping of the edges of the slots. In the arrangement shown in Fig. 5 the wire forming the cam-follower is of circular cross-section and the free end of the follower is bent at an acute angle to the shank. Further the edges 25 of the slot are vertical. In this case the acceleration imparted to a cam-follower upon engagement with a flank of a slot may be excessive. However, it is frequently found that continual operation of the device for a short period wears down the sharp edges of the slots, thus reducing the acceleration of the follower and the loading on the cam. These two effects cumulatively reduce the rate of wear and it is found that after a short period of running, the contour of the cam and hence the timing will remain substantially constant.

It may, however, be inconvenient to perform this initial running in operation in which case the follower of the edges of the slots may be specially shaped to reduce both the acceleration of the follower and the loading. For instance, as shown in Fig. 6, the leading edge 26 of the slot may be inclined and the free end of the follower is bent to form an obtuse angle with the shank or as shown in Fig. 7, the free end of the follower may have a V-shape. Again both these constructions may be included in a further embodiment. Another arrangement which avoids this disadvantage is shown in Figs. 8 and 9 where the leading and trailing edges of the slots are provided with flexible tongues 27 and 29. In this case, however, care must be taken to ensure that the base member or supporting member does not nullify these precautions. For instance as shown in Fig. 8, where the supporting member rotates with the disc, the base member should be provided with recesses such as 28 having the same width as the slots in the disc but slightly greater length. The flexible edges are shown at 27. Where the supporting member is fixed relative to the disc the recesses should extend in complete circles in the supporting member or, as shown in Fig. 9, an additional disc 30 may be inserted between the slotted disc 2 and the supporting member 5, the additional disc having similar slots 31 of slightly greater length than the slots in the disc 2.

It will, of course, be understood that while the embodiments described are arranged to control

a plurality of circuits, there is no limitation to more than one. Further, other alternative arrangements are possible and, in particular, the cam-followers could consist of spring-pressed balls. In addition the height of the contact pins or insets may be made variable to enable accurate adjustments to be made of the instants of making and breaking contact between the follower and the pin and also to enable compensation to be made for wear of the cam follower.

Other arrangements than the slotted disc may also be used. For instance, the sheet may be arranged in the form of a tube mounted on a cylinder or the sheet may be wrapped round a rotatable cylinder or cone. It may also be in the form of a tape which may be continuous where repetitive operation is required, the movement of the sheet being linear in this case.

The cam device of the invention has many applications. For instance, it may be employed for operating electric contacts which control the operation of flashing fluorescent lights. It may also be used for the generation of repetitive make and break signals which form, for example, the elements of a telegraphic code. Other applications will also be apparent to those skilled in the art.

I claim:

1. An electrical switching device comprising a shaft, means for rotating said shaft, a thin metallic disc secured to said shaft with its plane normal thereto so as to be rotatable therewith and provided with a plurality of rows of perforations at different radii, a plurality of contact members located in a plane parallel to the plane of said disc and spaced apart so as to register with said rows of perforations respectively, an insulating support for said disc located on the side thereof remote from said contact members, and metallic inserts in said support at radii corresponding to the contact-making ends of said contact members whereby as said disc is rotated said contact members make intermittent contact with said inserts.

2. An electrical switching device comprising a shaft, means for rotating said shaft, a thin metallic disc secured to said shaft with its plane normal thereto so as to be rotatable therewith and provided with a plurality of concentric rows of perforations, a plurality of contact members located in a plane parallel to the plane of said disc and spaced apart so as to register with said rows of perforations respectively, a fixed insulating support for said disc located on the side thereof remote from said contact members, and metallic inserts in said insulating support in positions opposite the contact-making ends of said contact members.

3. An electrical switching device comprising a shaft, means for rotating said shaft, a thin metallic disc secured to said shaft with its plane normal thereto so as to be rotatable therewith and provided with a plurality of concentric rows of perforations, a plurality of contact members located in a plane parallel to the plane of said disc and spaced apart so that their contact-making ends register with said rows of perforations, an insulating support for said disc located on the side thereof remote from said contact members and secured to said shaft so as to be rotatable therewith, metallic inserts in said support in positions corresponding to the perforations in said disc, slip rings on said shaft connected respectively to said inserts and brushes cooperating

with said slip-rings for making external connection to said inserts.

4. In a switching device as claimed in claim 1, the provision of flexible tongues at the leading edges of said perforations so as to reduce shock in the engagement of said disc with said contact members.

5. In a switching device as claimed in claim 3, the provision of a second metallic disc between said first disc and said insulating support, said second disc being provided with perforations registering with those in said first disc but slightly

longer in the direction of movement of said first disc and flexible tongues on the edges of said perforations on said first disc extending into the perforations of said second disc.
